(57) **CLAIM**

The ornamental design for a rack for shipping objects and/or displaying objects, as shown and described.

DESCRIPTION

FIG. 1 is a top, front-right pictorial view of a rack for shipping objects and/or displaying objects in accordance with the present invention;

FIG. 2 is a bottom, rear-left pictorial view of the rack of FIG. 1;

FIG. 3 is a right elevation view of the rack of FIG. 1;

FIG. 4 is a left elevation view of the rack of FIG. 1;

FIG. 5 is a front elevation view of the rack of FIG. 1;

FIG. 6 is a rear elevation view of the rack of FIG. 1;

FIG. 7 is a top plan view of the rack of FIG. 1; and,

FIG. 8 is a bottom plan view of the rack of FIG. 1.

In the drawings, the broken lines show portions of the rack that form no part of the claimed design.

1 Claim, 7 Drawing Sheets
